(57) **CLAIM**

The ornamental design for legs of a patient transport device having surface ornamentation, as shown and described.

DESCRIPTION

This application is related to U.S. patent application Ser. Nos. 29/458,151, entitled Control Panel of a Patient Transport Device Having Surface Ornamentation; 29/458,153 entitled Legs and Frame of a Patient Transport Device; and 29/442,947, entitled Patient Transport Device, filed concurrently herewith.

FIG. 1 is a right side elevational view of legs of a patient transport device having surface ornamentation illustrating an embodiment of my new design;

FIG. 2 is a left side elevational view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a left side perspective view thereof; and,

FIG. 8 is a bottom isometric view thereof.

The applied stipple type shading on the legs of a patient transport device having surface ornamentation indicates a contrast in appearance.

The broken lines in the drawings are included for the purpose of illustrating environmental structure and forms no part of the claimed design.
